UNITED STATES PATENT OFFICE.

EUGENE M. BEALS, OF CHICAGO, ILLINOIS, ASSIGNOR, BY MESNE ASSIGNMENTS, TO
WILLIAM E. PIERCE, OF DETROIT, MICHIGAN.

CALCULATING DEVICE.

1,286,797.

Specification of Letters Patent.

Patented Dec. 3, 1918.

Application filed October 15, 1915, Serial No. 56,053.

To all whom it may concern:

Be it known that I, EUGENE M. BEALS, a citizen of the United States, residing at Chicago, in the county of Cook and State 5 of Illinois, have invented certain new and useful Improvements in Calculating Devices, of which the following is a specification.

This invention relates to improvements 10 in calculating devices and more particularly to apparatus whereby the product of one figure multiplied by another may be instantaneously ascertained. The device is adapted primarily for use in figuring up 15 "time" in making out pay rolls, etc. The invention comprises a frame composed of two channeled parallel sides connected by strips of material whereon certain figures are arranged in a predetermined manner; 20 and a sheet of material movably disposed in the channeled portions of the frame and having arranged thereon columns of figures to be read in connection with the figures of the said strips.

25 More specifically the invention consists in the combination and arrangement of parts to be hereinafter fully described in the following specification, pointed out in the appended claim and illustrated in the accompanying drawing which forms a part of said specification and in which—

Figure 1 is a front elevation of my invention.

Fig. 2 is an end elevation of the same.

Fig. 3 is an enlarged fragmentary detail view of the same.

Like reference characters denote corresponding parts in the several views.

My invention comprises the frame members 1 and 2 of channeled formation and which are connected by the vertical strips 3 which are arranged in pairs, one member of each pair being disposed upon each side of the members 1, 2. Slidably arranged in 40 the channeled members 1, 2 between the several pairs of strips are sheets 4 preferably provided with handles 5 by means of which they may be adjusted individually with relation to the said strips. The frame member 2 is carried by a rotatable pedestal 6.

Each strip 3 is divided into marginal columns 7 and with relatively interior columns 8, the marginal columns bearing figures arranged in arithmetical progression 55 and the interior columns bearing figures

of an individual value of approximately one quarter the value of the figure directly opposite in the adjacent marginal column. The figures in the marginal columns denote the salary paid per hour, usually figured in 60 hundredths of a dollar, and the figures in the relatively inner columns denote the compensation for one quarter hour.

The sheets 4 are marked off into columns, the first and second columns which denote, 65 respectively, the rate per quarter hour in cents or hundredths of a dollar, and the number of hours to be figured. These columns are readable across the page or from left to right. Below the cross columns the 70 figures are readable in vertical columns and the numbers denote the compensation in hundredths of a dollar. A person working 27 hours at a salary of 10¢ per hour would find the remuneration due him at the inter- 75 section of a horizontal column, or a cross column, that included the rate "10" with a vertical column that included the time "27" which figure, as shown in Fig. 3, would be 270 hundredths of a dollar or \$2.70. Had 80 the party worked 27 and $\frac{1}{4}$ hours he would add the figure opposite "10" in the inner strip column, which is "3" and denotes that 3¢ should be added to the figure "270", making a total of \$2.73. If the party received 85 10 and $\frac{1}{4}$ ¢ per hour his compensation is figured by adding the rate per $\frac{1}{4}$ ¢ given at the head of the vertical column in which his number of hours appears. In the example given he would add 7¢ to his total which, at 90 10¢ per hour, would make the amount due him \$2.77.

The sheet 4 is movable so that it may be placed in such position that the vertical column containing the number of hours to 95 be included in the figuring is placed immediately next the marginal column of the strip 3. While the foregoing is the preferred form and arrangement of my invention it is understood that certain minor 100 changes and refinements may be resorted to all of which it is intended to anticipate by the following claim.

What is claimed is:—

In a calculating device, a pair of parallel 105 members having channels formed in their opposed faces, a plurality of spaced strips rigidly connecting said members, said strips having columns of figures extending longitudinally thereof, and a sheet of material 110

having opposite edges engaged by the channels of said members and carrying rows of figures alined respectively with the figures of said columns, said sheet being slideable in said channels transversely of the strips.

5 In testimony that I claim the foregoing as my own I have hereto affixed my signa-

ture in the presence of two subscribing witnesses.

EUGENE M. BEALS.
